United States Patent Office

Des. 215,692
Patented Oct. 28, 1969

215,692

STAPLING MACHINE

Maurice Charles Glennon, 15 Hornshay St.,
London SE. 15, England

Filed July 29, 1968, Ser. No. 12,932

Claims priority, application Great Britain Apr. 9, 1968

Term of patent 14 years

Int. Cl. D8—02

U.S. Cl. D8—49

FIG. 1 is a perspective view of a stapling machine showing my new device;

FIG. 2 is an elevational view thereof;

FIG. 3 is an elevational view of the end opposite to that seen in FIG. 1; and

FIG. 4 is a bottom plan view thereof.

I claim:

The ornamental design for a stapling machine, substantially as shown.
